WILLIE MARTIN BOWLES AND CHARLEY OSKER ALLEN, OF SHAWNEE, OKLAHOMA.

FURNACE FOR SMELTING AND REFINING ORES.

1,073,468.

Specification of Letters Patent.

Patented Sept. 16, 1913.

Application filed July 12, 1911. Serial No. 638,475.

To all whom it may concern:

Be it known that we, WILLIE M. BOWLES and CHARLEY O. ALLEN, citizens of the United States, and residents of Shawnee, in the county of Pottawatomie and State of Oklahoma, have made certain new and useful Improvements in Furnaces for Smelting and Refining Ores, of which the following is a specification.

10 Our invention relates to improvements in furnaces for smelting and refining ores, and it consists in the combinations, constructions and arrangements herein described and claimed.

15 An object of our invention is to provide a device by means of which ores such as those of zinc or lead may be smelted by means of the heat from an electric arc.

20 A further object of our invention is to provide a device by means of which the vapors of the metals may be condensed and may be drawn off.

25 A further object of our invention is to provide a device by which the soluble acid vapors may be gotten rid of.

Other objects and advantages will appear in the following specification, and the novel features of the device will be particularly pointed out in the appended claim.

30 Our invention is illustrated in the accompanying drawings forming part of this application in which similar reference characters indicate like parts in the views, and in which—

35 Figure 1 is a sectional view of a furnace constructed according to our invention, and Fig. 2 is a section along the line 2—2 of Fig. 1.

40 In carrying out our invention we provide a furnace comprising a main body portion 1, built of refractory material. This has an inclined hearth 2 at the front end of which is a well 3 having a refractory lining 4 of carbon or other conducting material. At

45 the bottom of the well is an outlet 6. Disposed centrally of the well is a carbon electrode 7 which is carried by a rack 8 arranged to be raised or lowered by a pinion 9 on a shaft 10 which is driven by a gear 11.

50 A guide member 12 is provided for the rack. A peep hole 13 is located in the front end of the furnace and above the hearth 2 is a cylindrical cover 14. The ore is designed to be fed by conveyers 15 into the side of the furnace through openings 16 above the

hearth 2. Disposed immediately above the

hearth 2 are a series of carbon electrodes 17 on one side and a similar series 18 on the other side. These electrodes may be adjusted toward or away from the opposing electrodes by means of a rack 19 and pinion 20 on a shaft 21 operated by a gear 22. In Fig. 2 we have shown one of these electrodes so adjusted, but it will be understood that the entire series of electrodes may be adjusted simultaneously by a similar contrivance. Leading from the upper end of the furnace is a tube 22 in which is a spiral screw conveyer 23 on a shaft 24 which may be driven by gear 25. The tube 22 is surrounded by an outer tube 26 at the bottom of which is an inlet 27 beneath which is a burner 28. At the end of the tube 22 is an outlet chute 29. The tube 22 communicates with a chamber 30 at the top of which is a conical condenser 31 having a water jacket 32. On the inner side of the condenser is a trough 33 having an outlet 34. From the top of the condenser 31 a pipe 35 leads downwardly into a water tank 36 which is supported on a frame 37 and which is provided with a drain cock 38.

From the foregoing description of the various parts of the device the operation thereof may be readily understood.

The ore is carried by means of the conveyer 15 into the furnace and deposited above the electrodes 17 and 18. When the current is turned on the intense heat of the arcs causes the smelting of the ore and the metal runs down the inclined hearth 2 into the well 3. Here it may be further refined by the arc between the electrodes 4 and 7, and may be drawn off through the outlet 6. In case the metal should vaporize or form, as in the case of zinc, "blue powder," the vapor or fumes are passed through the conveyer 22 where the powder is deposited. The operation of the conveyer serves to scrape the powder to the end of the conveyer where it is discharged through the chute 29. In order to regulate the temperature of the tube 22 we provide a burner 28 which heats the tube to the proper temperature for securing the best results. Any vapors which pass through the tube 22 may be further condensed in the condenser 31, which as stated is provided with a gutter or trough 33 for collecting the condensed vapors, the product being drawn off at the outlet 34. Any acid vapors or any gases which are soluble will pass through the pipe 35.

and down into the water tank 36, and will thereby be absorbed by the water. The latter may be drawn off through the top 38.

We claim:

- 5 In a device for smelting ores, a furnace, means for producing a series of arcs, means for introducing ore above said arcs, a tube leading from said furnace for condensing the metallic vapors, a screw conveyer for
- 10 scraping the walls thereof and for forcing the condensed product out of said tube, an

air jacket surrounding said screw conveyer, an opening into said air jacket beneath said tube, and a burner disposed at the mouth of said opening for heating the air 15 in the air jacket.

WILLIE MARTIN BOWLES.
CHARLEY OSKER ALLEN.
